UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed February 1, 1924. Serial No. 689,871.

To all whom it may concern:

Be it known that I, EDWARD S. STIMPSON, a citizen of the United States, residing at Hopedale, in the county of Worcester and

5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms whereby the operation of the loom is changed when the filling in the shuttle becomes substantially exhausted.

15 It is now the common practice to provide feeler mechanisms for looms which shall be effective to replenish the filling when that in the shuttle becomes substantially exhausted, and in some instances of such feeler mechanisms the feeler itself has been held in a 20 frontward retracted position for periods of time and then released to perform its feeling function, and the feeling mechanism has been so arranged that the release of the 25 feeler might take place at any stage in the cycle of loom operation. Consequently, it happens at times that the feeler will be released when the lay is moving frontwardly, or when the lay is nearly in front position, 30 with the result that the feeler impact with the filling has not only had an injurious effect upon the filling itself but such impact is liable to cause the feeler to call for a change of filling by premature movement.

35 Feeler mechanisms of the general type referred to may be known as "intermittent" feeler mechanisms and they are especially advantageous in connection with weaving with certain kinds of filling—such, for instance, as fine yarn, silk, and the like. The 40 feelers of such mechanisms are held in a frontward retracted position for periods of inactivity and are released from time to time for periods of activity, and one of the 45 objects of the present invention is to provide means for insuring the release of the feeler to its periods of activity when the lay is back or moving towards back position, so that the feeler may move to full feeling 50 position before engaging the filling.

An important feature of the present invention, therefore, consists in an intermittent feeler mechanism for looms wherein the feeler is released to its periods of activity 55 as the lay goes back, the effect being that

the feeler will commence its periods of activity to detect the condition of the filling in the shuttle in its rearward filling feeling position.

In accordance with the present invention, 60 the means for holding the feeler in its retracted position is associated with mechanism acting through said means to free the feeler as the lay goes back or retreats from front position.

65 The various features of the invention and new combination of parts will best be made clear from the following description and the accompanying drawings of one good form thereof, it being understood that the invention is in its true scope as defined by the 70 claims.

In the drawings:

Fig. 1 is a perspective view of one side of 75 a loom provided with the present invention, some of the parts being omitted for clearness of illustration;

Fig. 2 is an enlarged side elevation partly 80 in section of the ratchet and pawl mechanism actuated from the lay rock shaft; and

Fig. 3 is a view similar to that of Fig. 2 with the parts in another position.

The loom frame 1 has mounted at the front portion thereof brackets 2, one at each side of the loom, between which extends a 85 transverse or rock shaft 3, extending up from which is an arm 4 connected with an actuating member 5 at 6. Pivotedly mounted on the actuating member 5 at 7 is the finger 8 which is adapted to be engaged by 90 an operating member 9 and moved frontwardly thereby when the filling is to be changed or the operative condition of the loom is to be altered. The operating member 9 may be formed as part of or connected to the cam follower.

95 Mounted on the bracket 10 extending from the loom frame is a bell crank lever 11 one arm of which underlies the finger 12 connected to the part 8 and the other arm of which is connected to a transmitter 13, the construction being such that on filling exhaustion indicating movement of the feeler, the operating member will act through the train of mechanism described 100 to initiate filling replenishment.

105 The filling replenishing mechanism is not herein shown and described because it is now well known and the details thereof form no part of the present invention.

Adjustably mounted on the bracket or arm 14 extending from the shipper stand 15 is the feeler stand 16 which may be adjustably secured in place by the bolt 17, as usual. In the present instance the invention is shown as associated with a feeler of the inclined type, that is, a feeler which enters the shuttle in a direction inclined to the longitudinal axis thereof and is mounted for displacement laterally of the shuttle by the forward pressure, and while the present invention lends itself with advantage to this type of feeler mechanism, it is to be understood that the invention is not restricted thereto, but may be advantageously employed in connection with feeler mechanisms of other types.

The feeler 18, as indicated in Fig. 1, passes through the slide 19 which is itself connected to the transmitter 13, and the forwardly extending stem 20 of the feeler passes through a swivel block 21. A spring 22 is mounted on the stem 20 and interposed between the block 21 and the bridge or member 23 secured to the feeler, the tendency of the spring being to normally move the feeler into rearward feeling position. The parts so far described may be substantially the same as the corresponding parts in the patent to Edward S. Stimpson, No. 1,309,226, July 8, 1919.

The lay 24 may be of usual construction and has the shuttle box 25, the front wall of which is slotted at 26 for the entrance of the feeler 18. The shuttle 27 in which is mounted the filling carrier has its front wall slotted as at 28, as usual in this class of looms, the construction being such that as the lay moves forwardly on a detecting beat the feeler may enter the shuttle box and shuttle and detect the condition of the filling in the shuttle.

In accordance with the present invention the feeler is to be held in a forward or inoperative position for periods of time and is to be released at intervals to perform its feeling function. The relative lengths of the periods of activity and inactivity may vary and as shown in the present instance of the invention the feeler is provided with a projection 29 which is moved forwardly with the feeler when the latter is moved forwardly by the advancing filling in the shuttle. Connected to the feeler stand 16 is a bracket 30 to which is pivoted at 31 a lever 32 constituting the feeler holding means. The rear end portion of the lever 32 is laterally extended at 33, such lateral extension being adapted to engage the rear surface of the projection 29 on the feeler when the feeler is moved forwardly on a detecting beat with a working supply of filling in the shuttle. A spring 34 normally tends to move the feeler holding means 32 in its feeler holding position but is suffi-

ciently yieldable to permit the rear end of the feeler holding means to lift as the projection 29 of the feeler moves forwardly. The construction thus far described constitutes a good practical form of an intermittent feeler mechanism with which the present invention may be associated, but other details of intermittent feeler mechanisms may be employed advantageously in connection with the present invention, which relates more particularly to the feeler releasing means.

In accordance with the present invention, the feeler is to be released from its holding means at intervals so timed and arranged that the feeler release takes place when the lay is going back or retreating from front position so that the feeler may assume its periods of activity in rearward feeling position. In carrying out this feature of the invention, means are associated with the lay rocker shaft to transmit releasing movement to the feeler holding means as such rocker shaft and lay move towards the rear of the loom.

In the present instance, the loom frame 1 has secured thereto a bracket 35 located near the lower portion of the loom frame, from which extends a support or stud 36 for supporting the ratchet wheel, forming part of the train of mechanism for releasing the feeler. As shown, the ratchet wheel 37 is mounted in a frame 38, the upward extending portion 39 of which is secured to the stud 36 by stud screws 40, as indicated in Fig. 1. The supporting frame 38 is so formed as to protect as well as support the ratchet wheel 37.

The lay rocker shaft 41, best indicated in Figs. 2 and 3, extends as usual in a transverse direction between the side frames of the loom, and is supported in suitable bearings for rocking movement. It is not deemed necessary herein to fully illustrate and describe the bearings for the lay rocker shaft 41 since the details form no part of the present invention.

The portion of the lay rocker shaft extending beyond the side frames of the loom has secured to it a shoe or enclosing member 42, an outward extension 43 of which may be provided as a bearing surface for the rocker shoe 44 of the picker stick 45. These details, however, may vary within the scope of the present invention. Connected to the lay rocker shaft 41 is an arm 46, Figs. 2 and 3, which moves with the lay rocker shaft. As shown, the arm 46 is secured to the lay rocker shaft by a stud screw 47 which passes through the arm 46 at its lower portion and into the sleeve or shoe 42. The sleeve or shoe 42 may be itself secured to the rocker shaft 41 either by the screw 47 or an additional screw 48 may be employed as indicated in

Fig. 1, such details being within the selective skill of the mechanic.

The upper portion of the rocking arm 46 has extended therefrom a stud 49 on which is pivotally mounted a pawl 50 having a tooth 51 adapted to engage a tooth 52 of the ratchet 37, the construction being such that as the lay rocker shaft moves backwardly, as indicated by the arrow, Figs. 2 and 3, the pawl will impart to the ratchet wheel 37 a step-by-step rotary movement, and as the lay rocker shaft turns forwardly the pawl will click over the tooth of the ratchet wheel in its idle stroke. To prevent backward movement of the ratchet wheel during the idle stroke of the pawl, a check pawl 53 may be employed, as indicated in Figs. 2 and 3.

The pawl 50 is provided with a slot 54 through which passes a pin 55 which is secured to the rear face member of the bracket 38 and has an enlarged head 56 which acts to guide the pawl in its movements. Any usual form of guide may be employed for this purpose within the true scope of the invention.

The ratchet wheel 37 has one or more trip lugs 57 connected thereto. In the present instance, two of such trip lugs are indicated, but obviously the number of these may be varied, and such trip lugs may be removably secured to the ratchet wheel by passing the stem of the trip lug through one of the holes 58 formed in the face of the ratchet wheel.

Pivottally supported at 59 on the bracket 38 is an arm 60 which has a downwardly extending toe 61 adapted to be engaged by a trip lug 57 as the ratchet wheel is turned at its upper part towards the rear of the loom. The arm 60 carries a projection 62 on the upper surface of which rests the end portion of a flexible wire 63 which extends downwardly through an opening in the bearing 64 secured to the loom frame. If desired, the wire 63 may be mounted for lengthwise movement in a collar 65 which may be secured to the lug 64 by a screw 66 or other means.

The wire 63 extends upwardly and its upper end portion extends through a lug 67 formed in the bracket 30 and underlies a projection 68 formed on the feeler holding lever 32. Between the lugs or brackets 64 and 67 the wire 63 is encased or sheathed by a flexible covering 69, the construction being such that should the lower end of the wire 63 be moved by the projection 62 on the lever 60, the upper end of the wire 63 will be correspondingly moved to lift the feeler holding means or lever 32 to release the feeler.

In order to limit the movement of the arm 60, the latter may be provided with a stop 70 constituting a projection from the

arm 60 to engage the fixed bracket 64 on the loom frame when the arm 60 is in its normal position, as indicated in Fig. 2. When one of the trip lugs 57 passes under the shoe or projection 61 of the arm 60, the latter is raised, thereby moving the sheathed wire longitudinally and freeing the feeler to its periods of activity.

The shape, configuration and extent of the interengaging lugs 57 and 61 on the ratchet wheel 38 and arm 60 respectively are preferably such that more than a single toothed movement of the ratchet wheel is necessary to cause such lugs to pass into and out of engagement, the effect being that the feeler will first be released and will remain released from the feeler holding means for more than one beat-up movement of the lay and preferably for two or even three beats.

From the construction described it will be apparent that the feeler will be held in its frontward inoperative position and out of cooperative relation with the filling in the shuttle for periods of inactivity and that it will be released from the feeler holding means at intervals to its periods of activity, and that such release of the feeler to the performance of its feeling function takes place when the lay is not in a position to interfere with the movement of the feeler to its full feeling position. In other words, the release of the feeler to its periods of activity takes place when the lay and lay rocker shaft are moving towards the rear of the loom so that the feeler may assume its rearward feeling position without engaging the filling and will be in full feeling position to detect the condition of the filling on the next detecting beat.

What is claimed is:

1. In a feeler mechanism for looms the combination of a feeler, a catch for holding the feeler in a frontward, inoperative position during its periods of inactivity, a trip for said catch to free the feeler at intervals, the lay rocker shaft at the lower part of the loom, an arm secured to the lay rocker shaft for rocking movement therewith at the lower part of the loom, and means actuated by the arm as the rocker shaft turns backwardly for freeing the feeler from the catch at intervals.

2. In a feeler mechanism for looms in which the feeler has periods of activity and inactivity during weaving with the same supply of filling in the shuttle, the combination of a feeler, means for holding the feeler in a frontward inoperative position during its periods of inactivity, the lay rocker shaft mounted for rocking movement at the lower part of the loom, an arm secured to the lay rocker shaft, a ratchet wheel mounted adjacent to the lay rocker shaft and hav-

ing a trip lug, and means between the arm and ratchet wheel for actuating the latter to free the feeler from its holding means at intervals.

5. In a feeler mechanism for looms in which the feeler has periods of activity and inactivity during weaving with the same supply of filling in the shuttle, the combination of a feeler, means for holding the feeler

10 in a frontward inoperative position during its periods of inactivity, the lay rocker-shaft mounted for rocking movement at the lower part of the loom, an arm secured to the lay rocker-shaft, a ratchet wheel mounted ad-

15 jacent to the lay rocker shaft and having a trip lug, and a pawl connected to the arm for actuating the ratchet to free the feeler at intervals.

4. In a feeler mechanism for looms in which the feeler has periods of activity and inactivity during weaving with the same supply of filling in the shuttle, the combination of a feeler, means for holding the feeler in a frontward inoperative position

25 during its periods of inactivity, the lay rocker-shaft mounted for rocking movement at the lower part of the loom, an arm secured to the lay rocker-shaft, a ratchet wheel mounted adjacent to the lay rocker-

30 shaft and having a trip lug, a bracket secured to the loom frame for supporting the ratchet wheel for operation from the lay rocker-shaft, a pawl connected to the arm for stepping the ratchet wheel along as the

35 rocker-shaft swings the arm rearwardly to free the feeler from its holding means at intervals.

5. In a feeler mechanism for looms, the combination of a feeler, a catch for holding

the feeler in a frontward inoperative position during its periods of inactivity, a trip for said catch to free the feeler at intervals, the lay rocker-shaft at the lower part of the loom, an arm secured to the lay rocker shaft for rocking movement therewith at the lower part of the loom, a trip arm, a flexible sheathed wire between the trip arm and trip for freeing the feeler at intervals upon movement of the wire in its sheath, and means actuated by the backward movement 50 of the arm on the rocker shaft for actuating the trip arm.

6. In a loom, the combination of the lay rocker-shaft, a pawl connected thereto, a ratchet wheel actuated by the pawl as the lay moves back, a lug carried by the ratchet wheel, a feeler, a catch for holding the feeler in frontward inoperative position during periods of inactivity, and means between the catch and ratchet wheel for freeing the feeler from the catch as the ratchet wheel is actuated by the pawl on backward movement of the lay that the feeler may be freed at intervals to periods of activity.

7. In a feeler mechanism for looms, the combination of a feeler, a catch for holding the feeler in frontward inoperative position during periods of inactivity, the lay and lay rocker-shaft, a ratchet wheel, a pawl actuated from the lay rocker-shaft on backward movement to turn the ratchet wheel, and means between the ratchet wheel and catch including a flexible sheathed wire for tripping the catch and freeing the feeler to periods of activity as the lay goes back.

In testimony whereof, I have signed my name to this specification.

EDWARD S. STIMPSON.
